UNITED STATES PATENT OFFICE.

DAVID LAPPIN, OF MILWAUKEE, WISCONSIN.

DESIGN FOR AN ELECTRIC-LIGHT FIXTURE.

Application filed June 18, 1926. Serial No. 18,081. Term of patent 7 years.

To all whom it may concern:

Be it known that I, DAVID LAPPIN, a citizen of the United States, residing at Milwaukee, in the county of Milwaukee and State of Wisconsin, have invented a new, original, and ornamental Design for Electric-Light Fixtures, of which the following is a specification, reference being had to the accompanying drawing, forming part thereof.

The figure is a perspective view of an electric light fixture showing my new design.

I claim:

The ornamental design for an electric light fixture, as shown.

In testimony that I claim the foregoing I have hereunto set my hand at Milwaukee, in the county of Milwaukee and State of Wisconsin.

DAVID LAPPIN.
